UNITED STATES PATENT OFFICE.

HERMAN STELLING, OF NEW YORK, N. Y.

INDICATOR.

SPECIFICATION forming part of Letters Patent No. 624,562, dated May 9, 1899.

Application filed November 15, 1898. Serial No. 696,510. (No model.)

To all whom it may concern:

Be it known that I, HERMAN STELLING, a citizen of the United States, residing at New York, (Corona,) in the county of Queens and State of New York, have invented certain new and useful Improvements in Indicators, of which the following is a full and complete specification, such as will enable those skilled in the art to which it appertains to make and use the same.

This invention relates to indicators for use in restaurants, hotels, cafés, saloons, and similar places; and the object thereof is to provide an improved device of this class for use in connection with the tables usually employed in the places referred to.

The invention is fully disclosed in the following specification, of which the accompanying drawings form a part, in which the separate parts of my improvement are designated by the same numerals of reference in each of the views, and in which—

Figure 1 is a plan view of my improved indicator; Fig. 2, a cross-section on the line 2 2 of Fig. 1, and Fig. 3 a partial longitudinal section on the line 3 3 of Fig. 1.

In the practice of my invention I provide an indicator which comprises a plate or board 5, which is preferably provided with side strips 6, which prevent it from warping or twisting, and said plate or board is also provided with transverse wires or rods 7, which are partially countersunk therein, and with longitudinal spring-metal strips 8, which are secured thereto over said wires or rods. The plate or board is provided at the upper end thereof with a segmental portion or extension 9, which bears the numerals "1" to "6," inclusive, arranged in a segmentally-curved line thereon, and these numerals designate the tables in the place where the indicator is used, and said tables are in practice provided with corresponding numbers or numerals, and any desired number of these numbers or numerals may be used on the indicator, as will be readily understood. The indicator is also provided with a pivoted pointer 10, which operates in connection with the numbers or numerals referred to, and one side of the indicator is divided into spaces 11, and said spaces are mostly provided centrally with the names of the articles furnished in the café or restau-

rant where the indicator is employed. The upper two spaces referred to are provided with the numerals "10" and "5," which represent the price of the various articles, and the lower space is provided with the word "Paid."

The horizontal spring-metal strips 8 equal in number the numerals in connection with which the pointer 10 operates, and each of the transverse spaces formed by the transverse wires or rods 7 is provided with a plurality of pivoted blocks 12, which are held in place by screws 13, passed centrally therethrough and through the spring-metal strips 8, and each of the spaces formed by the transverse wires or rods 7 is thus provided with one of the pivoted blocks 12 for each of the longitudinal strips 8.

By providing the transverse wires or rods 7 and securing the spring-metal strips 8 thereover I form depressions in said spring-metal strips at the point where the pivoted blocks 12 are connected therewith, and these depressions cause said blocks to bind thereon, and thus the friction is increased and said blocks will not be accidentally moved or turned, but can be readily turned on their pivotal supports by means of the thumb and finger.

In the device shown in Fig. 1 the pointer 10 indicates table No. 2, and if a customer should come in and be seated at this table the waiter would take his order and turn the corresponding block 12, as indicated at 14. The waiter would also turn one of the blocks to indicate the price of the article ordered, as indicated at 15, and when the article is paid for another of said blocks would be turned to indicate the fact, as shown at 16. By means of this device the article ordered, the price thereof, and the fact that it has been paid for may always be clearly shown by the indicator, and it will thus be seen that I accomplish the object of my invention by means of a device which is simple in construction and operation and which is also comparatively inexpensive.

My invention is not limited to the exact form, construction, combination, and arrangement of parts herein described, and I reserve the right to make all such alterations therein and modifications thereof as fairly come within the scope of the invention.

Having fully described my invention, I claim as new and desire to secure by Letters Patent—

1. An indicator, comprising a plate or board provided at one end with a pointer and with a plurality of numerals arranged in a segmental line adjacent thereto, said plate or board being also provided with a corresponding number of longitudinal spring-strips beneath which are placed transverse wires or rods whereby the plate or board is divided into horizontal and transverse spaces, blocks pivotally connected with said spring-strips in each of said transverse spaces, said indicator being provided at one side with spaces formed by said rods or wires, substantially as shown and described.
2. An indicator, comprising a plate or board provided at one end with a pointer, and with a plurality of numbers arranged in a segmental line, adjacent thereto, said plate or board being also provided with a corresponding number of longitudinal spring-strips and transverse divisions, whereby the plate or board is divided into horizontal and transverse spaces, blocks pivotally connected with

said spring-strips and each of said transverse spaces, said indicator being also provided at one side with spaces corresponding with the transverse spaces thereof, substantially as 30 shown and described.

3. An indicator of the class described, provided at one end with a pointer and a numerical scale in connection with which said pointer operates, a plurality of parallel metal strips secured thereto, and each provided with a plurality of depressions, a plurality of longitudinal and transverse rows of pivoted blocks, each of which blocks is connected with one of said metal strips in one of the 40 depressions thereof, and said indicator being provided at one side with spaces corresponding with said transverse rows, substantially as shown and described.

In testimony that I claim the foregoing as 45 my invention I have signed my name, in presence of the subscribing witnesses, this 12th day of November, 1898.

HERMAN STELLING.
